HORN

Cecil S. Kelley, Forest Hills, Pa., assignor to The Westinghouse Air Brake Company, Wilmerding, Pa., a corporation of Pennsylvania

Application June 10, 1936, Serial No. 84,410

13 Claims. (Cl. 116—142)

This invention relates to an improved pneumatic horn and particularly to a device of the type employing a vibratory diaphragm.

It is an object of this invention to provide an improved pneumatic horn employing a vibratory diaphragm and in which the diaphragm is of rugged construction and will withstand severe usage without breaking.

A further object of the invention is to provide an improved horn adapted to produce a sound of large volume.

Another object of the invention is to provide an improved pneumatic horn which is operative in response to the supply of fluid under pressure throughout a wide range of pressures.

A further object of the invention is to provide a pneumatic horn of the type employing a vibratory diaphragm and having a diaphragm constructed of a plurality of laminations of material.

Another object of the invention is to provide a pneumatic horn having a diaphragm which is yieldable in response to variations in the pressure of fluid in a chamber on the face thereof and in which the vibrating portion thereof is of substantially greater weight or mass than the diaphragms now in use so that separate weights attached to the diaphragm are not required.

A further object of the invention is to provide a horn having a diaphragm having a central portion subject to the pressure of the fluid in a chamber and having arms projecting therefrom which are resiliently yieldable.

Another object of the invention is to provide a pneumatic horn having a resilient vibratory diaphragm subject to the pressure of the fluid in a chamber and having resiliently yieldable means for opposing movement of the diaphragm by the fluid under pressure in the said chamber.

A further object of the invention is to provide a pneumatic horn of the type described and incorporating means to adjustably vary the force exerted by the resiliently yieldable means and opposing movement of the diaphragm.

Another object of the invention is to provide an improved pneumatic horn incorporating means to adjustably vary the tone of the sound produced thereby.

A further object of the invention is to provide an improved pneumatic horn.

Another object of the invention is to provide an improved diaphragm unit adapted for use in pneumatic horns.

Other objects of the invention and features of novelty will be apparent from the following de-

scription taken in connection with the accompanying drawing, in which:

Fig. 1 is a sectional view of a horn embodying my invention,

Figs. 2, 3 and 4 are elevational views of elements employed in the horn shown in Fig. 1, and

Fig. 5 is a sectional view taken substantially along the line 5—5 of Fig. 1.

Referring to the drawing the horn therein illustrated comprises a body 1 and a cover 2 which are detachably secured together by means of cap screws 4. The body 1 has a bracket portion 5 formed integral therewith by means of which the horn may be secured to and supported from any suitable support, not shown.

The body 1 has a substantially annular flange 8 formed thereon and projecting from a face thereof and against which the cover 2 is secured. The cover 2 has formed thereon an annular flange 10 which is adapted to extend within the flange 8 on the body 1.

The body 1 also has formed thereon an annular seat rib 12 which projects from the adjacent portions of the body 1 and surrounds a chamber 14 which communicates through a choke 16 with a pipe 18 leading from a source of fluid under pressure. There is a chamber 15 outwardly of the seat rib 12 and within the flange 8 on the body 1.

A diaphragm device or unit indicated generally by the reference numeral 20 and comprising a plurality of members or laminations, as is best shown in Fig. 1 of the drawing, formed from suitable material, such as sheet metal, is provided. These members or laminations are duplicates of each other and each comprises a substantially circular disc having portions of the margin thereof cut away for a substantial distance, both radially and circumferentially, leaving a substantially circular central portion of

slightly larger diameter than the seat rib 12 on the body 1 and having projecting therefrom at points spaced apart circumferentially thereof radially extending arms 22 which gradually decrease in width away from the central portion, as is clearly shown in Figs. 2 and 5 of the drawing.

The arms 22 are of such length that when the diaphragm device 20 is positioned within the flange 8 on the body 1 there is a small amount of clearance between the ends of the arms 22 and the inner face of the flange 8.

The diaphragm device or unit 20 is shown in the drawing as constructed of six thicknesses or laminations of material, but the invention is not

limited to this number and a greater or fewer number of laminations may be employed.

The members or laminations of the diaphragm device or unit 20 are secured together by means of 5 a rivet 24 which extends through holes substantially at the center of these members or laminations, while washers 26 are mounted on the rivet 24 between the heads of the rivet and the faces of the diaphragm device 20.

10 The ends of the arms 22 of the diaphragm device 20 engage an annular spacing ring 28 formed of sheet metal or other suitable material and of substantially the diameter of the inner face of the flange 8 on the body 1.

15 The spacing ring 28 engages a face of a diaphragm 30 which is formed of a piece of suitable resilient material, such as sheet metal, and which is of substantially the diameter of the inner face of the flange 8 on the body 1. The other face of 20 the diaphragm 30 is engaged by the flange 10 on the cover 2, and the various parts of the horn are arranged and proportioned so that when the cover 2 is tightly secured to the body 1 by the cap screws 4 the spacing ring 28 presses against 25 the ends of the arms 22 on the diaphragm device 20 and presses the diaphragm device 20 against the seat rib 12 and deflects or bends the arms 22 slightly as shown in Fig. 1 of the drawing.

The diaphragm 30 has an opening 32 in the 30 central portion thereof and this opening is of somewhat smaller diameter than the central portion of the diaphragm device 20 so that the inner margin of the diaphragm 30 overlies the central portion of the diaphragm device 20.

35 The cover 2 has a centrally located bore therein in which is mounted a tubular bushing 34 which is formed of resilient yieldable material, such as moulded rubber, and which is adapted to engage the face of the diaphragm 30 adjacent 40 the inner margin thereof. A sleeve 36 is also positioned in the bore in the cover 2 and has a cylindrical portion which extends within the tubular bushing 34. The sleeve 36 also has a radially extending flange 37 thereon which engages the end of the tubular bushing 34, and this flange is of substantially the diameter of the bore in the cover 2 in which the bushing 34 is located.

The sleeve 36 has adjacent the end thereof a portion of smaller diameter than the flange 37 50 which cooperates with the cover 2 to form an annular chamber 38, while a plurality of ports 40 are provided which extend through the sleeve 36 and communicate with the chamber 38 and with the passage through the sleeve 36. In addition a plurality of passages 42 are formed in the cover 2 and communicate with the chamber 38 and with a chamber 44 on the face of the diaphragm 30 outwardly of the bushing 34. The cover 2 also has formed therein a passage 45 55 which communicates with the chamber 44 adjacent the lowermost portion thereof and with the atmosphere through which moisture may drain from the chamber 44 to the atmosphere.

A horn bell 46 provided with a threaded end 60 portion is adjustably secured in the bore in the cover 2 and is held in the adjusted position by means of a lock nut 48. The end of the horn bell 46 engages the end of the sleeve 36 and acts through the sleeve 36 to press the resilient bushing 34 against the diaphragm 30 and the force exerted by the bushing 34 on the diaphragm 30 65 may be adjustably varied by varying the position of the horn bell 46 in the cover 2.

In operation, when it is desired to blow the 70 horn, fluid under pressure is supplied to the pipe

75 by suitable means, not shown, and this fluid flows through the choke 16 to the chamber 14 on the face of the diaphragm device 20 within the seat rib 12. At this time the diaphragm device 20 is pressed against the seat rib 12 by the cover 2 acting through the arms 22 of the diaphragm device 20 so that fluid under pressure supplied to the chamber 14 cannot escape therefrom.

When the pressure of the fluid in the chamber 14 is increased to a predetermined value, the force 80 exerted by this fluid under pressure on the diaphragm device 20 is sufficient to force the central portion of the diaphragm device 20 away from the seat rib 12 and permit fluid under pressure to flow from the chamber 14 past the seat rib 12 to the chamber 15 outwardly of the seat rib 12. When the diaphragm device 20 moves 85 away from the seat rib 12 fluid under pressure may flow from the chamber 14 to the chamber 15 around the entire periphery of the seat rib 12.

The force required to move the central portion of the diaphragm device 20 away from the seat rib 12 is determined by the force required to bend the arms 22 of the diaphragm device. These arms are relatively long and narrow and extend 90 throughout a portion only of the circumference of the diaphragm device and offer much less resistance to movement of the central portion of the diaphragm device 20 than would be offered if the laminations of the diaphragm device were complete discs and did not have the portions intermediate the arms 22 cut away. As a result, therefore, the central portion of the diaphragm device 20 will yield in response to the force exerted thereon by fluid at moderate pressures in 95 the chamber 14 even though the diaphragm device is constructed of a plurality of laminations.

When the central portion of the diaphragm device 20 moves away from the seat rib 12 the arms 22 bend slightly, fulcruming on the spacing 100 ring 28, and the laminations of the diaphragm device 20 move relative to each other slightly, being free to do so as they are secured together only at the center. As the laminations of the diaphragm device 20 are free to move relative to 105 each other, the diaphragm device will bend or flex more easily than would a single diaphragm of the same thickness and mass as this diaphragm device which is built up of several laminations of material.

The diaphragm device 20, being constructed of 110 several thicknesses of material and having a central portion of substantial diameter, is relatively heavy, and when the central portion of the diaphragm device is moved away from the seat rib 115 12 the inertia of the diaphragm device tends to cause this portion of the diaphragm device to continue to move in this direction even after a reduction in the pressure of the fluid in the chamber 14 by the escape of fluid under pressure therefrom, and a corresponding reduction in the force 130 exerted by the fluid under pressure in the chamber 14 on the diaphragm device 20. The diaphragm device 20, therefore, will move away from the seat rib 12 beyond the point at which 135 the flow capacity of the opening across the seat rib 12 is large enough to permit fluid under pressure to escape from the chamber 14 as rapidly as fluid under pressure is supplied thereto through the choke 16, and as a result there will 140 be a rapid reduction in the pressure of the fluid in the chamber 14 and a similar rapid increase in the pressure of the fluid in the chamber 15.

When the central portion of the diaphragm device 20 is moved away from the seat rib 12 it 145

engages a portion of the diaphragm 30 adjacent to the inner margin thereof so that further movement of the diaphragm device 20 in this direction is opposed by the diaphragm 30 and by the resilient bushing 34.

When the diaphragm device 20 engages the inner marginal portion of the diaphragm 30 it forms a seal which cuts off communication between the chamber 15 and the atmosphere through the horn bell 46. In addition, as the diaphragm 30 is pressed against the resilient bushing 34 communication between the passage through the horn bell 46 and the chamber 44 is cut off.

On an increase in the pressure of the fluid in the chamber 15 as a result of the supply of fluid under pressure thereto from the chamber 14 there is an increase in the force exerted on the diaphragm 30 and tending to move the central portion of this diaphragm against the resilient bushing 34.

The diaphragm 30 being constructed of a single thickness of material is more flexible than the diaphragm device 20 which is built up of a plurality of laminations of material. In addition, the diaphragm 30 has a much larger area subject to fluid under pressure in the chamber 15 than the area on the face of the diaphragm device 20 which is subject to the pressure of the fluid in the chamber 14 so that on a slight increase in the pressure of the fluid in the chamber 15 by flow from chamber 14, to a value substantially below the pressure of the fluid in the chamber 14, the diaphragm 30 is moved farther from its normal position than the diaphragm device 20 is moved away from the seat rib 12 by the fluid under pressure in the chamber 14.

As soon as the pressure of the fluid in the chamber 15 is increased to a relatively low value, therefore, the force exerted by this fluid under pressure on the diaphragm 30 is sufficient to move the diaphragm 30 against the resilient bushing 34 away from the central portion of the diaphragm device 20 so as to permit fluid under pressure to escape from the chamber 15 to the atmosphere through the opening 32 in the diaphragm 30 and through the horn bell 46.

On an increase in the pressure of the fluid in the chamber 15, the difference between the pressure of the fluid in this chamber and in the chamber 14 within the seat rib 12 is reduced, and the rate of flow of fluid under pressure from the chamber 14 to the chamber 15 is correspondingly reduced.

If the rate of supply of fluid under pressure through the choke 16 to the chamber 15 is relatively slow, as when the pressure of the fluid supplied to the pipe 18 is at a low value, the central portion of the diaphragm device 20 will be moved a relatively small distance away from the seat rib 12 and fluid under pressure will flow from the chamber 14 to the chamber 15 at a comparatively slow rate to increase the pressure of the fluid in the chamber 15 somewhat and thereby reduce the rate of flow of fluid from the chamber 14 to the chamber 15.

As the central portion of the diaphragm device 20 is moved away from the seat rib 12 only a small distance, it is pressed lightly upon the inner margin of the diaphragm 30 and forces it against the resilient bushing 34 until a small amount of resistance to movement of the diaphragm 30 is developed as a result of the inherent resiliency of the material of which the diaphragm is constructed, and of the force exerted

by the resilient bushing 34 and opposing movement of the diaphragm 30.

As there is relatively weak resistance to movement of the diaphragm 30 the pressure of the fluid in the chamber 15 must increase only to a relatively low value before the force exerted by this fluid on the diaphragm 30 is able to move the diaphragm 30 farther against the resilient bushing 34 away from the diaphragm device 20 so as to permit fluid under pressure to escape from the chamber 15 to the atmosphere, and when the pressure of the fluid in the chamber 15 has been reduced by the escape of fluid therefrom, the diaphragm 30 will move back toward the diaphragm device 20 to restrict the rate of flow of fluid from the chamber 15 and maintain the pressure of the fluid in the chamber 15 at a predetermined value below the pressure of the fluid in the chamber 14 within the seat rib 12.

If the rate of flow of fluid under pressure through the choke 16 to the chamber 14 is relatively rapid, as when the pressure of the fluid supplied to the pipe 18 is at a comparatively high value, a high pressure will be developed in the chamber 14 and the central portion of the diaphragm device 20 will be moved a relatively great distance away from the seat rib 12 and it will engage the inner margin of the diaphragm 30 and press it against the resilient bushing 34 until considerable resistance to movement of the diaphragm 30 is developed.

On movement of the diaphragm device 20 away from the seat rib 12 fluid under pressure flows from the chamber 14 to the chamber 15 and increases the pressure of the fluid in the chamber 15. As there is considerable resistance to further movement of the diaphragm 30 against the resilient bushing 34 at this time, the pressure of the fluid in the chamber 15 must increase to a relatively high value before the force exerted on the diaphragm 30 is sufficient to move the diaphragm 30 farther against the resilient bushing 34 and away from the central portion of the diaphragm device 20 to permit fluid under pressure to escape from the chamber 15 to the atmosphere through the opening in the diaphragm 30 and the horn bell 46, while the diaphragm 30 will move back towards the diaphragm device 20 to reduce the rate of flow of fluid under pressure from the chamber 15 to the atmosphere before the pressure of the fluid in the chamber 15 is decreased to the same extent that it is reduced when the rate of supply of fluid under pressure to the chamber 14 through the choke 16 is relatively slow and the amount of deflection on the diaphragm device 20 away from the seat rib 12 is relatively small.

It will be seen, therefore, that the pressure of the fluid in the chamber 15 varies with variations in the pressure and the rate of supply of fluid to the chamber 14 so that the differential between the pressures in the chambers 14 and 15 remains substantially the same regardless of variations in the pressure of the fluid supplied to the pipe 18, and hence the rate of flow of fluid from the chamber 14 to the chamber 15 will be approximately the same at all times.

Because of the mass of the central portion of the diaphragm device 20, when this diaphragm is set in motion away from the seat rib 12 it continues to move away from the seat rib 12 until a passage is opened to permit fluid under pressure to escape from the chamber 14 to the chamber 15 which is somewhat larger than is required to permit fluid under pressure to escape

from the chamber 14 to reduce the pressure of the fluid in this chamber to a value such that the force exerted by the fluid in the chamber 14 on the diaphragm device 20 is unable to maintain the diaphragm device in the position to which it has been moved.

As the diaphragm device 20 moves to a position to open a relatively large passage across the seat rib 12, fluid under pressure will be released from the chamber 14 at a relatively rapid rate so that the pressure of the fluid in the chamber 14 is quickly reduced to a value insufficient to maintain the central portion of the diaphragm device 20 in the position to which it has been moved, and the diaphragm device 20 is thereupon moved back towards the seat rib 12 due to the inherent resiliency of the material of which it is constructed.

When the central portion of the diaphragm device 20 is moved towards the seat rib 12 the inertia of this portion of the diaphragm device causes it to continue to move in this direction until it engages the seat rib 12, and thereby cuts off the release of fluid under pressure from the chamber 14 past the seat rib 12 to the chamber 15.

On this movement of the central portion of the diaphragm device 20, the central portion thereof is moved away from the inner margin of the diaphragm 30 and the fluid in the chamber 15 may escape at a rapid rate to the atmosphere through the opening 32 in the diaphragm 30 and through the horn bell 46.

The resilient bushing 34 remains in sealing engagement with the face of the diaphragm 30 during these movements of the diaphragm 30, and of the diaphragm device 20, and prevents the flow of fluid from the passage in the horn bell 46 to the chamber 44 on the face of the diaphragm 30 outwardly of the bushing 34 where it might interfere with the movement of the diaphragm 30 by the fluid under pressure in the chamber 15.

The volume of the chamber 44 varies with movement of the diaphragm 30 and fluid under pressure may flow to or from this chamber at restricted rates through the passages 42 in the sleeve 36, the chamber 38 and the passages 42 in the cover 2, or through the drain passage 45. The passages 42 and 45 also provide means for the escape of fluid under pressure from the chamber 44 in case any fluid under pressure flows from the horn bell past the resilient bushing 34 to the chamber 44.

When the diaphragm device 20 is moved back into engagement with the seat rib 12 and the escape of fluid under pressure from the chamber 14 is cut off, the pressure of the fluid in this chamber increases because of the continued supply of fluid under pressure thereto through the choke 16. Because of the relatively small volume of the chamber 14, the pressure of the fluid in this chamber is quickly increased to a value such that the force exerted on the diaphragm device 20 is sufficient to overcome the force tending to hold the central portion of the diaphragm device 20 in engagement with the seat rib 12. The diaphragm device 20 will thereupon be moved away from the seat rib 12 to again permit fluid under pressure to escape from the chamber 14 to the chamber 15 and the cycle of operation described above is repeated.

The movements of the central portion of the diaphragm device 20 out of engagement with the seat rib 12 and into engagement therewith occur

very rapidly and result in the creation of a rapid series of vibrations in the air column within the horn bell 46 with the result that an audible sound is produced.

The pitch of the note produced by the horn is determined by the length of the horn bell, and the rate of vibration of the diaphragm device 20 must be in tune with the rate of vibrations of the air column in the horn bell 46 in order for the horn to operate most effectively and give a sound of maximum volume and clarity of tone.

The rate of vibration of the diaphragm device 20 is regulated by the rate at which fluid under pressure may escape from the chamber 14 to the chamber 15 and therefrom to the atmosphere through the opening 32 in the diaphragm 30 and the passage through the horn bell 46.

The release of fluid under pressure from the chamber 15 may be varied by varying the adjustment of the horn bell 46 in the cover 2, and thereby varying the force exerted by the resilient bushing 34 on the diaphragm 30 and opposing movement of the diaphragm 30 by the fluid under pressure in the chamber 15. This also varies the pressure to which the fluid in the chamber 15 must be increased before fluid under pressure is released therefrom and thereby influences the difference between the pressure of the fluid in the chamber 15 and in the chamber 14, and thus influences the rate of flow of fluid from the chamber 14 which governs the vibrations of the diaphragm device 20.

While one embodiment of the improved pneumatic horn and diaphragm provided by my invention has been illustrated and described in detail, it should be understood that the invention is not limited to these details of construction and that numerous changes and modifications may be made without departing from the scope of the following claims.

Having now described my invention, what I claim as new and desire to secure by Letters Patent, is:

1. In a sound producing device, in combination, a casing having a chamber therein, a vibratory diaphragm device mounted in said chamber, means for causing said diaphragm device to vibrate, said diaphragm device comprising a plurality of laminations of material, each of the laminations of the diaphragm device having a central portion and having projecting therefrom radially extending arms, and a member engaged by the ends of said arms whereby said arms are flexed upon movement of said diaphragm device.

2. In a sound producing device, in combination, a casing having a chamber therein, a vibratory diaphragm device mounted in said chamber, means for causing said diaphragm device to vibrate, said diaphragm device comprising a plurality of laminations of material, each of the laminations of the diaphragm device having a central portion and having projecting therefrom radially extending arms, said arms decreasing in width away from the said central portion, and a member engaged by the ends of said arms whereby said arms are flexed upon movement of said diaphragm device.

3. In a sound producing device, in combination, a casing section having a seat rib associated therewith, a diaphragm device formed of a plurality of laminations each having a central portion and having arms extending radially therefrom, the central portion of the lamination on one face of the diaphragm device being of larger diameter than the said seat rib and being adapted

to engage said seat rib, means engaging the other face of the diaphragm device adjacent the ends of the said arms for pressing the diaphragm device into engagement with said seat rib, and means for supplying fluid under pressure to the area within said seat rib.

5. In a sound producing device, in combination, a casing section having a seat rib associated therewith, a diaphragm device formed of a plurality of laminations each having a central portion and having arms extending radially therefrom, means extending through openings located substantially centrally of said laminations for securing said laminations together, the central portion of the lamination on one face of the diaphragm device being of larger diameter than the seat rib and being adapted to engage said seat rib, means engaging the other face of the diaphragm device adjacent the ends of the said arms for pressing the diaphragm device into engagement with said seat rib, and means for supplying fluid under pressure to the area within the said seat rib.

6. In a sound producing device, in combination, a casing section having a seat rib associated therewith, a diaphragm device formed of a plurality of laminations each having a central portion and having arms extending radially therefrom, the central portion of the lamination on one face of the diaphragm device being of larger diameter than the said seat rib and being adapted to engage said seat rib, means engaging the other face of the diaphragm device adjacent the ends of the said arms for pressing the diaphragm device into engagement with said seat rib, and means for supplying fluid under pressure at a restricted rate to the area within said seat rib.

6. In a sound producing device, in combination, a casing section having a seat rib associated therewith, a diaphragm device formed of a plurality of laminations each having a central portion and having arms extending radially therefrom, the arms decreasing in width away from said central portion, the central portion of the lamination on one face of the diaphragm device being of larger diameter than the said seat rib and being adapted to engage said seat rib, means engaging the other face of the diaphragm device adjacent the ends of the said arms for pressing the diaphragm device into engagement with said seat rib, and means for supplying fluid under pressure to the area within said seat rib.

7. In a sound producing device, in combination, a casing having a chamber therein and having a seat rib associated therewith and projecting into said chamber, means for supplying fluid under pressure to the area within said seat rib, a diaphragm device mounted in said chamber and adapted to have a face thereof engage said seat rib, the diaphragm device being subject to the pressure of the fluid within the seat rib and controlling the flow of fluid under pressure from the area within said seat rib to the chamber in said casing outwardly thereof, a diaphragm element subject to the pressure of the fluid in said chamber, said diaphragm element being movable relative to the diaphragm device by the fluid in said chamber, and means controlled by said diaphragm device and by said diaphragm element for releasing fluid under pressure from said chamber.

8. In a sound producing device, in combination, a casing having a chamber therein and having a seat rib associated therewith and projecting into said chamber, means for supplying fluid

under pressure to the area within said seat rib, a diaphragm device mounted in said chamber and adapted to have a face thereof engage said seat rib, the diaphragm device being subject to the pressure of the fluid in the area within the seat rib and controlling the flow of fluid under pressure from the area within said seat rib to the chamber in said casing outwardly thereof, a diaphragm element subject to the pressure of the fluid in said chamber, said diaphragm element being movable relative to the diaphragm device by the fluid in said chamber, and means responsive to relative movement between said diaphragm device and said diaphragm element for releasing fluid under pressure from said chamber.

9. In a sound producing device, in combination, a casing having a chamber therein and having a seat rib associated therewith and extending into said chamber, two diaphragm units mounted in said chamber, one of said diaphragm units having a face adapted to engage the seat rib, said diaphragm unit being subject to the pressure of the fluid in the area within said seat rib and controlling the flow of fluid under pressure from the area within said seat rib to the chamber in said casing outwardly thereof, said diaphragm unit being arranged to be deflected a given distance from the seat rib on an increase in the pressure of the fluid within said seat rib to a given value, the other of said diaphragm units being subject to the pressure of the fluid in said chamber outwardly of said seat rib and being arranged to be deflected farther than said given distance on an increase in pressure of the fluid in said chamber to a value less than said given value, and means controlled by relative movement of said diaphragm units for releasing fluid under pressure from said chamber.

10. In a sound producing device, in combination, a casing having a chamber therein and having a seat rib associated therewith and projecting into said chamber, means for supplying fluid under pressure to the area within said seat rib, a diaphragm device mounted in said chamber and adapted to have a face thereof engage said seat rib, the diaphragm device being subject to the pressure of the fluid in the area within said seat rib and controlling the flow of fluid under pressure from the area within the seat rib to the chamber in said casing outwardly thereof, a diaphragm element subject to the pressure of the fluid in said chamber, means yieldingly opposing movement of said diaphragm element by the fluid in said chamber, and means controlled by said diaphragm device and said diaphragm element for releasing fluid under pressure from said chamber.

11. In a sound producing device, in combination, a casing having a chamber therein and having a seat rib associated therewith and projecting into said chamber, means for supplying fluid under pressure to the area within said seat rib, a diaphragm device mounted in said chamber and adapted to have a face thereof engage said seat rib, the diaphragm device being subject to the pressure of the fluid in the area within said seat rib and controlling the flow of fluid under pressure from the area within the seat rib to the chamber in said casing outwardly thereof, a diaphragm element subject to the pressure of the fluid in said chamber, biasing means yieldingly opposing movement of said diaphragm element by the fluid in said chamber, means to adjustably vary the force exerted on said diaphragm element by said biasing means, and

means controlled by said diaphragm device and said diaphragm element for releasing fluid under pressure from said chamber.

12. In a sound producing device, in combination, a casing having a chamber therein and having a seat rib associated therewith and projecting into said chamber, means for supplying fluid under pressure to the area within said seat rib, a diaphragm device mounted in said chamber and adapted to have a face thereof engage said seat rib, the diaphragm device being subject to the pressure of the fluid in the area within said seat rib and controlling the flow of fluid under pressure from the area within the seat rib to the chamber in said casing outwardly of the seat rib, a diaphragm element subject to the pressure of the fluid in said chamber, said diaphragm ele-

ment being movable relative to the diaphragm device by the fluid in said chamber, said diaphragm element having an opening substantially centrally thereof, the face of the diaphragm element surrounding said opening being adapted to be engaged by the diaphragm device to control communication between said chamber and said opening. 5

13. A diaphragm device for use in a signaling device and having relatively large mass together with a high degree of flexibility, the diaphragm device comprising a plurality of thicknesses of material each having a central portion providing a large mass and having radially extending arms projecting therefrom providing a high degree of 10 flexibility. 15

CECIL S. KELLEY.
